[57] CLAIM

The ornamental design for a resilient clip for retaining removable lenses in an eyeglass frame, substantially as shown and described.

DESCRIPTION

FIG. 1 is a front elevation of a resilient clip for retaining removable lenses in an eyeglass frame and showing our new design;

FIG. 2 is a top plan view thereof;

FIG. 3 is an inverted rear elevation thereof;

FIG. 4 is a bottom view thereof; and

FIG. 5 is a side elevation thereof.

The structure shown in broken lines in the drawings is merely illustrative of a typical eyeglass on which the clip of our design is useful.
